UNITED STATES PATENT OFFICE

165,257

PORTABLE FILTER PRESS KIT

Glen W. Anderson, Oildale, and Durward B. Jones, Bakersfield, Calif.

Application December 19, 1950, Serial No. 13,500

Term of patent 7 years

(Cl. D91—1)

To all whom it may concern:

Be it known that we, Glen W. Anderson and Durward B. Jones, citizens of the United States, residing at 719 Washington Avenue, Oildale, California, and 2730 Buena Vista, Bakersfield, California, respectively, have invented a new, original, and ornamental Design for a Portable Filter Press Kit, of which the following is a specification, reference being had to the accompanying drawing, forming part thereof.

Fig. 1 is a perspective view on a reduced scale of the portable filter press kit, showing my new design in a closed position for transportation.

Fig. 2 is a front elevation of the kit completely open.

Fig. 3 is a perspective view of the kit partially open; and

Fig. 4 is a plan view of the closed kit.

The dominant features of our design reside in the portions shown in full solid lines.

We claim:

The ornamental design for a portable filter press kit, as shown and described.

GLEN W. ANDERSON.
DURWARD B. JONES.
